UNITED STATES PATENT OFFICE.

WILLIAM H. HAIGHT, OF NORTHFIELD, MINNESOTA.

KNOCKDOWN FURNITURE.

1,298,496.

Specification of Letters Patent. Patented Mar. 25, 1919.

Application filed June 2, 1917. Serial No. 172,417.

To all whom it may concern:

Be it known that I, WILLIAM H. HAIGHT, a citizen of the United States, resident of Northfield, in the county of Rice and State 5 of Minnesota, have invented certain new and useful Improvements in Knockdown Furniture, of which the following is a specification.

The object of this invention is to provide 10 a piece of furniture of simple and inexpensive construction, and one which may be easily assembled or taken apart for shipping or packing.

A further object is to provide a piece of 15 furniture which may be easily adjusted to various positions to suit the comfort of the user.

Other objects of the invention will appear 20 from the following detailed description.

The invention consists generally in the 25 various constructions and combinations all as hereinafter described and particularly pointed out in the claims.

In the accompanying drawings forming 30 part of this specification,

Figure 1 is a side elevation of the frame, set at a height to form a bed or cot, the dotted lines showing how the same frame may be adjusted to form a hammock,

Fig. 2 is a plan view of the same frame as shown in Fig. 1, with the fabric broken away,

Fig. 3 is a design of the same style of frame in elevation showing how it may be 35 changed to form a chair,

Fig. 4 shows the device adjusted to form a reclining chair,

Fig. 5 is a sectional view on the line 5, 5 of Fig. 4,

Fig. 6 is a detail view showing the means 40 for fastening the corners of the frame,

Fig. 7 is a sectional view on the line 7, 7, of Fig. 1.

In the drawings, 2 represents the principal side members forming the frame, there 45 being two of the same on each of the opposite sides. 3 represents the bearing cross bars and 4 and 5 respectively the foot and top bars connecting the two sides of the 50 frame together. 6 is a clamp provided for securing the cross members of the frame from slipping and for otherwise strengthening the joint. 7 shows the fabric covering forming the seat or mattress and 8 denotes 55 the terminating hem of the same, inclosing a stretcher.

It will be observed that I have made a departure from the common method of securing the cross members of the frame, in that I have eliminated the usual pin, each of the 60 end sections being secured together and independent of the other, and being adapted to slip to and from each other freely, and always having a proper bearing, the effect of this movement being to raise or lower the 65 frame as desired.

By having this bearing the whole frame is greatly strengthened, and increased weight on the seat serves to make it more rigid, the fact that the bearing bars extend 70 across the frame from side to side being an added factor to its rigidity.

As will be seen by reference to Fig. 1 the bearing bars are set upon the top of the crossed members. In the operation of 75 changing from a cot or couch to a hammock position, the sides of the upper angle are lengthened, and in the case of the reclining modification of the chair as exhibited in Fig. 4, the bearing bars being on the under 80 side of the crossed members, it will be observed that the same operation produces a contrary effect, as the sides of the angle are shortened, these effects being desirable in either case.

As it is my purpose to use a choice of many different methods of fastening the cross bars to the side members I make only one showing of this feature, but in any case, whether I use plain bolts with thumb nuts, 90 a pin and socket device, angle plates secured with bolts, or other means, I intend to make the connection so that the said members may be interchangeable to either the top or bottom of the braces.

I also propose to provide multiple holes in the crossed side braces so that when desirable, either of the bearing bars may be adjusted to a different position, relative to the ends, so that the two ends of the frame may 100 be made of different heights.

While there may always be considerable binding weight on the crossed joint of the frame, the added body weight on the covering tends to raise the extreme upper ends of 105 the frame, the draft being toward the joint, and in the case as shown in Fig. 1 it becomes necessary to provide strong clamps to prevent the joint from slipping. Such a clamp is shown in detail in Fig. 7. This is 110 of wood, and long enough to straddle the joint when the frame is in any position, the

binding being made by simply turning thumb nuts on the securing bolts at each end.

In the modified construction as shown in Figs. 3 and 4 so strong a clamp is unnecessary and if any it used it will be more nearly automatic.

The covering 7 may be of any desirable fabrics, and either as a whole or in concentrated strands, running over the end or ends of the frame, to the end that the length and tension may be adjusted to the frame as desired.

I make no claim as to the fastening, as the choice of several means may be used.

When desirable, as in its use in hospitals for wounded, the covering may be loose from the frame and adjustable at both ends, so it may be easily and quickly changed when soiled or infected.

It is my desire to provide a simple and comparatively inexpensive device that may be quickly put together or taken apart, closed up and set aside when not in use, making a small and compact bundle for shipping or use in traveling; making a desirable couch that may be raised to a bed at any height, or altered to a hammock or reclining chair; all of the same general construction.

In various ways the details of construction herein shown and described may be modified and still be within the scope of my invention.

I claim as my invention:

1. A device of the class described comprising a pair of substantially rectangular frames, the side rails of one frame being arranged to cross the corresponding rails of the other frame, cross bars intermediate to the ends of said frames, the cross bar of one frame forming a rest and support for the upper portion of the other frame and allowing a slidable adjustment of said frames one upon the other for varying their height and angle with respect to the ground line, said cross bars being interchangeable from the top side of one frame to the underside of the other to adapt them for different articles of furniture, and a filler of flexible material adjustably connected to the upper ends of said frames.

2. A device of the class described comprising a pair of substantially rectangular frames, the side rails of one frame being arranged to cross the corresponding rails of the other frame, cross bars intermediate to the ends of said frames, the cross bar of one frame forming a rest and support for the upper portion of the other frame and allowing the adjustment of said frames one upon the other for varying their angle with respect to the ground line to adapt them for

different articles of furniture, and a filler of flexible material connected to the upper ends of said frames.

3. A device of the class described comprising frames having side rails and end cross bars between them, intermediate bars mounted on said side rails, the rails of one frame being positioned to cross those of the other frame and rest upon the intermediate cross bar of said other frame, one of said frames having guiding strips mounted thereon and spaced therefrom, forming slots wherein the rails of said other frame are slidable, and a flexible filler attached to the upper ends of said frame.

4. A device of the class described comprising a pair of substantially rectangular frames, the side rails of one frame being arranged to cross the corresponding rails of the other frame, strips mounted in parallel relation with the side rails of one of said frames and forming therewith guides for the corresponding rails of the other frame, cross bars adjacent to said guiding strips and mounted on the upper edges of said rails, the cross bar of one pair of rails forming a rest and support for the rails of the other frame, and a filler of flexible material adjustably connected to the upper ends of said frames.

5. A device of the class described comprising a pair of substantially rectangular frames, the side rails of one frame being arranged to cross the corresponding rails of the other frame and guides for longitudinal adjustment of said frames one upon the other to adapt them for different articles of furniture, cross bars mounted on said frames adjacent the point where the rails of one frame cross the rails of the other frame and the cross bar of one frame forming a rest and support for the rails of the other frame, and a flexible filler having its ends attached to the upper portions of said frames and adjustable thereon.

6. A device of the class described comprising a pair of substantially rectangular frames, the side rails of one frame being arranged to cross the corresponding rails of the other frame, cross bars intermediate to the ends of said frame, the crossbar of one frame forming a rest and support for the upper portion of the other frame and allowing slidable adjustment of said frames one upon the other, a filler of flexible material, wider and longer than said frames and seated on the upper ends thereof, rods mounted in the ends of said filler, and means for adjustably securing said rods on said frames.

In witness whereof, I have hereunto set my hand this 28th day of May 1917.

WILLIAM H. HAIGHT.
